UNITED STATES PATENT OFFICE.

JOEL C. R. PALMER, OF NEW ROCHELLE, NEW YORK, ASSIGNOR TO WESTERN ELECTRIC COMPANY, OF NEW YORK, N. Y., A CORPORATION OF ILLINOIS.

TELEPHONE SYSTEM.

1,148,923.

Specification of Letters Patent. Patented Aug. 3, 1915.

Application filed May 10, 1913. Serial No. 766,863.

To all whom it may concern:

Be it known that I, JOEL C. R. PALMER, a citizen of the United States, residing at New Rochelle, in the county of Westchester and State of New York, have invented a certain new and useful Improvement in Telephone Systems, of which the following is a full, clear, concise, and exact description.

This invention relates to a common battery telephone system and more particularly to a transmission system for comparatively long lines with which are associated a plurality of substations.

The object of this invention is to provide a novel and improved combination of substation circuit apparatus whereby a plurality of substations on the same line may be efficiently operated from a common battery source.

This invention is particularly adapted for use with systems having a plurality of substations on a single telephone line, such for instance, as train despatching or fire control systems, said substations being arranged to be brought into circuit simultaneously with the office of the central operator or despatcher for the purpose of receiving a general order. Heretofore, this has been impracticable in common battery telephone systems, due to the division of the available current between the various stations which limits the current for each transmitter to a quantity less than is desirable for good transmission.

This feature may be overcome by cutting out the flow of current through a substation, except when its transmitter is in actual use, and the invention resides in providing a closed path for telephonic current in bridge 40 of the telephone line, said bridge containing a receiver and means for preventing the flow of direct current through said bridge, and additional means for including a transmitter in said bridge.

In the embodiment of this invention in a telephone set, switching means is provided at each substation normally completing the receiving circuit in bridge of the line through a condenser, and is arranged when operated to connect a transmitter in said

bridge and to include a low impedance path in shunt of the receiver.

In the accompanying drawings, Figure 1 represents a substation circuit in which this invention is embodied; Fig. 2 shows the circuit and apparatus which is bridged across the telephone line when the receiver is on the switch hook; Fig. 3 shows the receiving circuit when the receiver is removed from the switch hook; and Fig. 4 shows the arrangement of the receiving and transmitter circuits when the switching means is operated.

Referring to the drawings, and particularly to Fig. 1, 5 and 6 designate the line wires forming the telephone line, which unites the various substations (only one shown) with the central office (not shown). At each substation is located a ringer 10 and a condenser 11 in series therewith, which are at all times bridged across the line wires 5 and 6. At each station is a high impedance receiver 12 having in series therewith a condenser 13, the receiver and condenser being adapted to be placed in bridge 75 of the line wires 5 and 6 by the operation of the receiver switch hook 14 which closes switch hook contact 15, said bridge including a normally closed contact 16, 17 of a switch key 18. Operation of the switch hook 14 also closes contact 20, which places a shunt around the condenser 11, to form a path for direct current between the line wires.

A secondary 25 of an induction coil 26 is bridged directly across the line wires 5 and 6 in series with a non-inductive tapering resistance 27 and a transmitter 28 by the closure of the normally open contacts 16, 29 and 30, 31, 32 of the switch key 18. The tapering resistance 27 is non-inductive and the value thereof differs for each station, the purpose of the resistance being to compensate for line resistance between stations so that each station will receive the same amount of current. By the closure of contacts 30, 31, 32 of the switch key 18, the receiver 12 and condenser 13 are bridged around the transmitter 28 in series with a primary 33 of the induction coil 26, and a 100

low impedance path 34 is placed in shunt of the receiver 12.

Assuming now that an operator at the substation is listening and receiving a message, switch key 18 remains in the position shown and the path for the incoming voice currents includes the receiver 12 and the condenser 13 in bridge directly across the line wires 5 and 6, as shown in Fig. 3. When the operator at the substation desires to talk over the line, he actuates switch key 18, opening contacts 16, 17 and closing contacts 16, 29 and 30, 31, 32. The opening of the contacts 16, 17 disconnects the receiver 12 and condenser 13 from the line wires 5 and 6. Closing the contacts 16, 29 and 30, 31, 32 bridges the transmitter 28 directly across the telephone line in series with induction coil secondary 25 and tapering resistance 27, and associates therewith for the outgoing voice currents a local amplifying circuit including induction coil primary 33, condenser 13, low impedance path 34 and transmitter 28. At the same time a changed path is provided for the incoming voice currents including the induction coil primary 33, condenser 13 and receiver 12. The amplifying circuit through the inductive action of the condenser 13 amplifies the undulations set up by the transmitter 28. A detailed description of such an amplifying circuit is to be found in Patent 669,710 of March 12, 1901 to C. E. Scribner.

What I claim is:

35. 1. In a telephone transmission circuit, a telephone line, a normally open high impedance receiving circuit connected with said telephone line, a switch for closing said receiving circuit, a normally open transmitter circuit, and switching means for closing said transmitter circuit and simultaneously connecting said receiving circuit in shunt of said transmitter circuit.
45. 2. In a telephone transmission circuit, a telephone line, a condenser, a normally open high impedance receiving circuit connected with said telephone line through said condenser, a switch for closing said receiving circuit, a normally open transmitter circuit, and switching means for closing said transmitter circuit and simultaneously connecting said condenser and said high impedance receiving circuit in shunt of the transmitter.
55. 3. In a telephone transmission circuit, a telephone line, an induction coil having two windings, a normally open high impedance receiving circuit connected with said telephone line, a switch for closing said receiving circuit, a normally open transmitter circuit including one winding of said induction coil, and switching means for simultaneously closing said transmitter circuit and connecting said high impedance receiving circuit in shunt of said transmitter circuit.
60. 4. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, and switching means for closing said receiving circuit, a normally open transmitter circuit including one winding of said induction coil, a normally open transmitter circuit including one winding of said induction coil, and switching means for closing said transmitter circuit and connecting said high impedance receiving circuit including said condenser in shunt of said transmitter circuit.
70. 5. In a telephone transmission circuit, a telephone line, an induction coil having two windings, a condenser, a normally open high impedance receiving circuit connected with said telephone line, a switch for closing said receiving circuit, a normally open transmitter circuit including one winding of said induction coil, and switching means for closing said transmitter circuit and connecting said high impedance receiving circuit including said condenser in shunt of said transmitter circuit.
75. 6. In a telephone transmission circuit, a telephone line, an induction coil having two windings, a normally open high impedance receiving circuit connected with said telephone line, a switch for closing said receiving circuit, a normally open transmitter circuit including one winding of said induction coil, and switching means for closing said transmitter circuit and simultaneously reducing the impedance of the receiver circuit and connecting it in shunt of said transmitter circuit.
80. 7. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, and switching means for closing said transmitter circuit and simultaneously reducing the impedance of the receiver circuit and connecting it in shunt of said transmitter circuit.
85. 8. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
90. 9. In a telephone transmission circuit, a telephone line, an induction coil having two windings, a condenser, a normally open high impedance receiving circuit connected with said telephone line, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
95. 10. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
100. 11. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
105. 12. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
110. 13. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
115. 14. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit including said induction coil primary, a condenser and a non-inductive resistance, and switching means for closing said transmitter circuit and said local amplifying circuit.
120. 15. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit, a low impedance path, and switching means for simultaneously reducing the impedance of said receiver circuit and connecting it in shunt of said transmitter circuit.
125. 16. In a telephone transmission circuit, a telephone line, an induction coil having two windings, a condenser, a normally open high impedance receiving circuit connected with said telephone line through said condenser, a switch for closing said receiving circuit, a normally open transmitter circuit including one winding of said induction coil, a normally open local amplifying circuit for said transmitter circuit, a low impedance path, and switching means for simultaneously reducing the impedance of said receiver circuit and connecting it in shunt of said transmitter circuit.

ceiving circuit, connecting said condenser and said low impedance path in said local amplifying circuit, closing said transmitter circuit, inductively associating therewith
5 said receiving circuit, and connecting said local amplifying circuit in shunt of said transmitter circuit.

In witness whereof, I hereunto subscribe my name this 7th day of May A. D., 1913.

JOEL C. R. PALMER.
